UNITED STATES PATENT OFFICE.

ALEXANDER DOMBROWSKY, OF LAS CASCADAS, PANAMA.

TROUSERS-CREASER.

1,004,390.

Specification of Letters Patent. Patented Sept. 26, 1911.

Application filed February 28, 1911. Serial No. 611,484.

To all whom it may concern:

Be it known that I, ALEXANDER DOMBROWSKY, a citizen of the United States, and a resident of Las Cascadas, Panama, have 5 invented certain new and useful Improvements in Trousers-Creasers, of which the following is a specification.

This invention is an improvement in trousers creasers and has for an object to 10 provide a simple and novel construction which will be efficient in use, is made in sections which can be conveniently detached to permit the device to be packed in small space and which can be quickly set up for 15 use, and the invention consists in certain novel constructions and combinations of parts as will be hereinafter described and claimed.

In the drawing Figure 1 is a side view of 20 the invention as in use. Fig. 2 is an edge view of one of the side clamps. Fig. 3 is a detail perspective view illustrating the construction at the meeting ends of the members of one of the side bars. Fig. 4 is a 25 detail perspective view of one of the clasps.

As shown, the creasers includes a pair of 30 side clamps A, which clamps are alike, so that a description of one will answer for both and these side clamps A are provided 35 at their upper ends with bows B, and a yoke C connects these bows, being provided with portions C' fitting within the bows and with projections C² which engage the inner edges of the bows so that the intermediate 40 spring portion C³ of the yoke, when its compressing ring D is moved to the dotted line position shown in Fig. 1, may operate to force the opposite side clamps apart to secure a stretching of the trousers at the foot 45 end thereof, as will be understood from Fig. 1 of the drawing.

One of the side clamps is shown in detail 50 in Fig. 2 and from this figure and Fig. 1 of the drawing, it will be noticed that the side clamp includes side bars A' having members A² and A³ which are fitted end to end and are detachably connected at their meeting ends by means of a box E on the end of the section A² and open at one side 55 E' forming the spring wings E², which have inwardly projecting ribs E³ which enter corresponding notches A¹³ in the tenon A¹⁴ at the end of the member A³. By this means

the sections of the side bars can be conveniently connected and disconnected and 55 when connected will be held against accidental detachment by the engagement of the ribbed spring wings E² with the meeting end of the section A³. At their upper ends the side bars are secured to their respective 60 arms of the bow B and may spring apart by the action of said bow when the clasps F are released, as indicated by the dotted lines at the lower end of the right hand clamp A in Fig. 1. The clasps F which are arranged 65 at intervals along the side clamps are composed of spring wires having each a side member pivoted at F² to the outer face of one of the side bars of the clamp bent between its ends at F³ and connected by a 70 cross-bar F⁴ which may be coiled at F⁵ midway between its ends, with the opposite side member F⁶, which engages on the outer side of the side bar complementary to that to which the clasp is pivoted at F², as will be 75 understood from Figs. 1, 2 and 4 of the drawing. By adjusting the clasp in the dotted line position X shown in Fig. 1 to the full line position shown in said figure, it will operate to hold the side bars of the 80 clamp firmly upon the trousers to be creased. If desired, the clamps may be made one longer than the other to adapt them for use at the front and rear edges of the trousers leg as shown in Fig. 1. 85

I claim:

1. A trousers creaser substantially as herein described, consisting of a pair of side clamps, each clamp comprising a top bow, and side bars secured at their upper ends to 90 their respective arms of the bow and made in sections fitting end to end and detachably connected at their meeting ends, clasps arranged at intervals along the side clamps, and a yoke connecting the bows of the opposite side clamps and engaging with said bows and having an intermediate spring portion adapted when freed to force the opposite bows apart, and means for compressing the said intermediate portion, substantially as 95 set forth.

2. In a trousers creaser, a side clamp comprising side bars made in sections fitting end to end, a box on one of the sections and open at one side and having an inwardly projecting rib or ribs at said side and the meeting 105

section being notched to receive said ribs or projections whereby the parts are interlocked, substantially as set forth.

3. The combination in a trousers creaser, of side clamps and a yoke connected with the opposite side clamps and extending therebetween and having an intermediate spring portion adapted when freed to press the op-

posite side clamps apart and means for compressing said intermediate portion, substantially as set forth. 10

ALEXANDER DOMBROWSKY.
